UNITED STATES PATENT OFFICE

OLOF OGREN, OF BRADDOCK, PENNSYLVANIA

ROTARY ENGINE

Application filed January 28, 1930. Serial No. 424,015.

This invention relates to rotary engines and has relation more particularly to a device of this kind adapted for use in connection with steam or other fluids, and it is an object of the invention to provide a device of this character constructed in a manner to obtain maximum efficiency from the motive fluid.

Another object of the invention is to provide a device of this kind which in its assembly is compact without sacrifice of power.

An additional object of the invention is to provide a device of this kind comprising a stator and a rotor, the stator being divided into a plurality of chambers and the rotor 15 having a part working in each of said chambers, adjacent chambers being in communication one with the other whereby the motive fluid passes in succession from one chamber to the other, thus assuring high efficiency.

20 The invention consists in the details of construction and in the combination and arrangement of the several parts of my improved rotary engine whereby certain important advantages are attained and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:—

35 Figure 1 is a view in side elevation of an engine constructed in accordance with an embodiment of my invention, the side face plate being removed;

Figure 2 is a vertical sectional view taken 40 substantially on the line 2—2 of Figure 1 with both side face plates applied;

Figure 3 is a side elevational view of one of the impellers as herein employed;

Figure 4 is a view in front elevation of the 45 impeller as illustrated in Figure 3;

Figure 5 is a sectional view taken substantially on the line 5—5 of Figure 2 looking in the direction of the arrow, the rotor being omitted;

50 Figure 6 is a view in top plan of the in-

ternal partition or wall of the stator unapplied;

Figure 7 is a view in side elevation of the partition or wall as illustrated in Figure 6;

Figure 8 is a sectional view taken substantially on the line 8—8 of Figure 1.

As disclosed in the accompanying drawings, S denotes the stator comprising a substantially cylindrical shell or casing 1 having its end portions provided with the outstanding flanges 2, the lower portion of each of such flanges being formed to provide a supporting means for the stator. It is to be understood, however, that the stator may be held in desired working position in any way preferred.

Substantially midway the ends thereof the stator has tightly mounted therein a partition or wall 3 whereby the stator S is divided into two chambers X and Y, the chamber Y 70 being of greater volumetric capacity than the chamber X.

The ends of the casing or shell 1 are closed by the end face plates or heads 4, each of which being shown as held in position by the 75 removable threaded members or screws 5.

Each of the plates or heads 4 is also preferably provided at diametrically opposed points with the inwardly directed pilot pins 6 for engagement within properly positioned openings 7 formed in an adjacent flange 2 whereby the proper application of the plate or head 4 is facilitated. It is to be understood that the screws 5 hereinbefore referred to are engaged with the remaining openings 7.

Disposed through the stator S and suitably supported by the applied plates or heads 4 and the partition or wall 3 is a shaft 8 from which power is adapted to be taken off in any manner desired.

The opposed faces of the partition or wall 3 and the plates or heads 4 are provided with the outstanding circular bearing blocks 9 preferably integral with said heads and partition or wall. These blocks 9 are coplanar 95 in a direction lengthwise of the shaft 8 and concentric to the center of the internal chambers of the stator S.

Within each of the internal chambers of the stator S is a rotor R comprising a rim 11

concentric to the shaft 8 and of a width to snugly engage between opposed faces of the partition or wall 3 and a plate or head 4. This rim 11 is connected by an interposed web 12 with a hub 14 mounted upon the shaft 8 and keyed thereto, as at 15, in any preferred manner. The rotor R is of such diameter and the shaft 8 is so located that the upper portion of the rotor R is at all times in close contact with the upper inner face of the peripheral wall of the stator S and at substantially the vertical center hereof whereby a desired abutment is maintained at all times.

The rim 11 of each of the stators is provided in its periphery and at diametrically opposed points with the transverse slot or groove 16 extending entirely thereacross and also extending down within the web 12.

Extending through each of these slots 16 is the blade 17 of an impeller A, said blade being of a width to snugly engage between the opposed faces of the partition or wall 3 and a plate or head 4 and having its outer edge face substantially in contact at all times with the internal peripheral wall of the chamber of the stator in which it operates.

One end portion of the blade 17 is provided with an inwardly disposed arm or shank 18 terminating in an annular member or ring 19 which is snugly engaged around a block 9 so that as the rotor revolves the blade 17 as a result of the coaction between a block 9 and the annular member or ring 19 will maintain the desired contact of the outer edge of the blade 17 with the internal peripheral wall of the chamber in which the rotor is operating. This action, however, results in a slight rocking movement of the blade 17 and to compensate for this movement the slot 16 in which the blade 17 operates is gradually widened from its outer end in a direction inwardly of the rotor as is particularly illustrated in Figure 1. The opposed walls of the slot 16 in relatively close proximity to the periphery of the rim 11 carry the rocking bars 20. As particularly illustrated in Figure 1, each of these bars 20 has a flat face constantly in contact with a flat side face of the blade 17. These bars 20 may be made of any desired material but preferably steel. These bars 20 constitute wear members and can be readily removed and replaced as the requirements of practice may necessitate.

One of the chambers of the stator to one side of its vertical center has the casing or shell 1 provided with an internal pocket 21 into which discharges a line 22 leading from a suitable source of fluid supply, such as steam, compressed air or water under pressure.

This chamber of the stator at the opposite side of its vertical center is provided with a second pocket 23 which communicates with a passageway 24 extending through the up-

per portion of the partition or wall 3 in a direction substantially at right angles to its axial center. This pocket 23 registers with a circumferentially disposed pocket or recess 25 provided in that portion of the periphery of the partition or wall 3 coincident with the pocket 23.

The passageway or port 24 delivers within an internal pocket 26 in communication with the second chamber and at the same side of the vertical center of the stator as the pocket 21 hereinbefore referred to. This pocket 26 has in register therewith a pocket or recess 27 provided in the adjacent peripheral face of the partition or wall 3. This second chamber of the stator has a second inwardly facing pocket 28 at the same side of the vertical center of the stator as the pocket 23. The pocket 28 has leading therefrom an exhaust pipe 29.

As the fluid enters through the pipe line 22 its action will effect the desired rotation of rotor R in the first chamber and such fluid will pass out through the pocket 23 and passageway or port 24 and through the pocket 26 into the second chamber for proper action upon the impellers in the second chamber of the stator, thus assuring a maximum of efficiency being obtained from the fluid.

From the foregoing description it is thought to be obvious that a rotary engine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In a rotary engine, a stator having a cylindrical bore therethrough, end members for closing each end of the bore, a shaft rotatably supported by said end members, a pair of rotors secured to said shaft, a partition disposed in said bore between said rotors and dividing said bore into a high pressure and low pressure chamber, impellers disposed in each chamber, means for rotatably supporting certain of said impellers from said end members, and means for rotatably supporting certain others of said impellers from said partition, said partition having a passage therethrough communicating with each chamber, said stator having an inlet discharging into one of said chambers, and an outlet exhausting from the other of said chambers.

2. In a rotary engine including a stator having a cylindrical bore therethrough, end members for closing each end of the bore, a

shaft rotatably supported by the end members, a pair of rotors secured to said shaft for rotation therewith and a plurality of impellers; a partition disposed in said bore and secured to said stator intermediate said rotors and dividing said bore into a high pressure and a low pressure chamber, annular bearings integrally formed with said end members and engaging certain of said impellers whereby to rotatably support said certain impellers in each chamber and annular bearings disposed on each side of said partition and engaging certain others of said impellers whereby to rotatably support said other impellers within each chamber, said partition having a passage therethrough communicating with each chamber, said stator having an inlet discharging into one of said chambers, and an outlet exhausting from the other of said chambers.

3. In a rotary engine including a stator having a cylindrical bore therethrough, end members for closing each end of the bore, a shaft rotatably supported by the end members, a pair of rotors secured to said shaft for rotation therewith and a plurality of impellers; a partition disposed in said bore and secured to said stator intermediate said rotors and dividing said bore into a high pressure and a low pressure chamber, annular bearings integrally formed with said end members and engaging certain of said impellers whereby to rotatably support said certain impellers in each chamber and annular bearings disposed on each side of said partition and engaging certain others of said impellers whereby to rotatably support said other impellers within each chamber, said partition having a passage therein extending transversely of the shaft and terminating at each end in a lateral passage tapering in the direction of rotation of said rotors whereby to completely exhaust the fluid from the high pressure chamber, said stator having an inlet discharging into one of said chambers, and an outlet exhausting from the other of said chambers.

In testimony whereof I hereunto affix my signature.

OLOF OGREN.
